UNITED STATES PATENT OFFICE

WILLIAM A. BLANKENSHIP, OF TAYLORSVILLE, NORTH CAROLINA

RAILWAY-CROSSING SIGNAL

Application filed June 8, 1928. Serial No. 283,866.

This invention relates to new and useful improvements in railway crossing signals and aims to provide a simply constructed and positively operable mechanism for association with a railway adjacent a road crossing and adapted to be operated by the movement of the train upon the railway toward the crossing to operate a visible signal whereby motorists or pedestrians will be notified that a train is approaching the crossing, this structure doing away with the usual presence of a signal man or an electrically operated alarm device now usually employed.

In the drawings wherein like reference characters indicate corresponding parts throughout the several views:

Figure 1 is a fragmentary plan view of a trackway at a road crossing, said trackway being equipped with my improved signal device.

Figure 2 is a fragmentary side elevation thereof.

Figure 3 is a detail transverse section taken through the mechanism operable by a member associated with the cow catcher or other convenient point in the forward end of the locomotive so as to cause the operation of the device when the locomotive approaches the crossing.

Figure 4 is a section through one of the track rails adjacent the road crossing looking toward the signal unit per se, and

Figures 5 and 6 are detail perspectives of certain elements of the device.

Now having particular reference to the drawings, A designates fragmentarily a trackway, and B the highway crossing.

In carrying out the present invention there is arranged upon one of the rail ties at the outer side of one of the rails and at a point remote from the highway crossing B a bracket 5 including a pair of upstanding arms 6—6 at the opposite ends thereof. Journalized through registering openings in the arms of

this bracket is a shaft 7, while keyed to the outer end thereof is a depending lever 8. Keyed to the shaft 7 between the arms 6—6 of said bracket is a collar 9, the inner face of which is formed with a cam surface, the high and low points thereof merging into a

shoulder 10. Loose upon said shaft 7 is the lower circular end 11 of an upstanding arm 12, the face of the lower end of said arm adjacent the cam surface of the collar 9 being also formed with a cam surface, the high and low points of which merge into a shoulder 13. Between the lower end of this arm 12 and the adjacent arm 6 of the bracket 5 is an expansible coil spring 14 for normally maintaining the lower end of the arm 12 in engagement with the face of the collar 9. Normally the shoulder 13 has engagement with the shoulder 10 of the collar 9 so that when the arm 12 is swung forwardly toward the roadway B as disclosed by the dotted lines in Figure 2 said shaft 7 will rotate for swinging the lever 8 in a rearward direction as also disclosed by the dotted lines in Figure 2. This arm 12 is swung in the direction just mentioned through the medium of an outwardly extending horizontal bar or other similar member 14 arranged upon the cow catcher or at any other suitable point at the forward end of a locomotive as suggested by the dotted lines in Figures 2 and 3.

Arranged upon the outer end of one of the rail ties adjacent the road crossing B and at the same side of the trackway as the other mechanism just described is a suitable bracket 16 through which is journalized a shaft 17, while associated with the outer end of this shaft is a right angularly extending semaphore arm 18 upon the outer end of which is a suitable sign plate 19. Keyed to the inner end of this shaft 17 is an arm 20 extending in the same direction as the semaphore arm 18. Interconnecting the lever 8 of the shaft 7 and the semaphore arm 18 is a tie rod or cable 21.

The arm 12 is normally maintained in the vertical position illustrated in Figure 2 by retractile coil springs 22 arranged at their opposite ends with the said arm 12 and the adjacent ties in the trackway as in Figures 1 and 2.

Obviously the normal position of the semaphore arm 18 is downwardly alongside the adjacent rail of the trackway as in said Figures 1 and 2. When a train approaches, the arm 15 upon the front end of the locomotive will strike the arm 12 forcing the same for-

wardly in the position disclosed by the dotted line in Figure 2, this will cause a pull upon the tie rod or cable 12 for obviously raising the semaphore arm 18 to the dotted line position in Figure 2.

As soon as the train reaches the upstanding member 20 said arm 15 will strike thereagainst as illustrated in Figure 4 for returning the semaphore to its downwardly swung 10 inoperative position.

It will thus be seen that I have provided a highly novel, simple and positively operating signal for railroad crossings, even though I have herein shown and described the invention as consisting of certain detail structural elements it is nevertheless to be understood that some changes may be made therein without departing from the spirit of the invention and the scope of the appended 20 claim.

Having thus described the invention, what I claim as new and desire to secure by Letters Patent is:—

In a railroad crossing signal of the character described, a semaphore arm pivoted at one side of the trackway adjacent the roadway, a shaft mounted for rotation at the same side of the trackway remote from said roadway, a vertically extending arm loosely 25 associated with said shaft, complementary construction between the shaft and said arm to cause the rocking of the shaft when the arm is moved downwardly toward the roadway, means for normally maintaining the arm in 30 vertical position so as to be engaged by means associated with a train passing over the trackway, means interconnecting said shaft and said semaphore arm whereby to cause the raising of the semaphore arm when said 35 shaft is rocked by the swinging of its associated arm, and means associated with the semaphore arm and adapted to extend upwardly when said semaphore arm is raised to be engaged by the means associated with 40 said train, whereby to cause the downward movement of the semaphore arm as the train 45 approaches the crossing.

In testimony whereof I affix my signature.
WILLIAM A. BLANKENSHIP.
